COATING APPARATUS

Edward H. Rand, Brooklyn, N. Y., assignor to
 Rand Rubber Company, Brooklyn, N. Y., a corporation of New York

Application September 5, 1942, Serial No. 457,481

1 Claim. (Cl. 91—12)

This invention relates to a novel coating apparatus and more particularly to a coating apparatus for and method of applying a film such as an adhesive in the form of an annulus on one or both faces of a member which may be a disc, which coated area or areas may be adjacent the periphery of the member to be coated.

Prior to the instant invention, in coating plane members with adhesives in special designs such as annular designs, it has been necessary to effect the coating more or less by hand with the utilization of a mask or guide or stencil. When both sides of the member are to be so treated, it has formerly been necessary to wait until the first side has become dry prior to coating the second side. When the first side is dry, the work is turned over and the second side treated in the same manner as the first side has been treated. Particularly in the coating of lenses with an annulus of cement on both sides of the lens adjacent the periphery, this prior method has been found to be slow, costly and non-uniform.

It is another object of the instant invention to provide a novel apparatus for uniformly and speedily coating a plane member with a film in the shape of an annulus.

It is a further object of this invention to provide an apparatus for simultaneously coating both sides of a disc with adhesive in the shape of an annulus on each side of said disc and adjacent the periphery thereof.

It is still a further object of the instant invention to provide an apparatus for speedily and efficiently applying a cement film in the shape of an annulus adjacent the periphery of lenses such as acetate gas mask lenses or windows.

Other objects and the nature and advantages of the invention will be apparent from the following description taken in conjunction with the accompanying drawing, wherein:

Figure 1 is a top plan view of coating apparatus in accordance with the invention;

Fig. 2 is an end view with parts omitted of the apparatus shown in Figure 1;

Fig. 3 is a coated acetate lens treated with the apparatus shown in Figs. 1 and 2; and

Fig. 4 is a fragmentary sectional view of the coated lens shown in Fig. 3.

Referring to the drawing, the pulley 10 is adapted to be driven by a belt connected to a driving shaft of an engine or motor. The pulley 10 is rigidly keyed to the shaft 11 to which is rigidly secured the driving gear 12 which meshes with the large driven gear 13 to effect speed reduction of the gear 14 which is formed integral

with the gear 13. The gears 13 and 14 are secured to the shaft 15 which is adapted to rotate in a first direction. The gear 14 meshes with the gear 16 which is secured to the shaft 17 which rotates in a second or opposite direction to the rotation of the shaft 15.

The frame F supports the shafts 15 and 17 in bearing relation. The frame F' supports the shaft 11 in bearing relation. At the opposite end 10 of the frame from the location of the pulley 10, the trough 18 is located. The trough is dished out and adapted to contain the film forming material which may be adhesive. The coating wheels 19 and 20 each of which are secured to the ends 15 of the shafts 15 and 17 respectively, dip into the trough 18 as best shown in Figure 2. The coating wheels 19 and 20 may be generally disc-shaped and knurled on their cylindrical surfaces. While in the preferred embodiment of the invention the 15 coating wheels are knurled, the knurling may be omitted and the surfaces may be smooth.

Adjustably supported on the cross member 21 of the frame F is the guide member G which, as shown in Fig. 1, substantially abuts the inner sides 25 of the coating wheels 19 and 20. The guide member G is arranged so that it can be locked in more than one position depending on the manner in which the work is to be coated or treated and the final design desired. In line with the axis of the 30 guide G and in the outer wall 22 of the trough 18 is formed the notch or groove 23 which serves as a guide for work to be passed between the coating wheels 19 and 20.

In carrying out the method in accordance with 35 the invention the work such as the acetate disc 24, shown in Fig. 3, is held between the forefinger and index or middle fingers of the operator and an edge thereof is inserted between a pair of coating wheels, such as the wheels 19 and 20, 40 until the edge of the work abuts the guide 17 and a continuation of the edge rests in the groove or slot 23 of the trough 18. Rotation of the coating wheels 19 and 20 toward each other as shown by the arrows in Fig. 2, effects application of the 45 coating medium such as the adhesive 25 to the disc 24 in the shape of an annulus on each side of the disc evenly, neatly and speedily.

The rotation of the wheels 19 and 20 effects 50 simultaneous rotation of the disc 24 by frictional contact. It is conceivable, however, that in accordance with the invention the work such as the disc 24 might be rotated by a third member which would hold the work with a suction cup or equivalent means. When the method is so carried out,

frictional contact would not be necessary though it would be essential that the film picked up by the coating wheels 19 and 20 contact the surface to be coated of the work 24.

The wheels 19 and 20 may be of any suitable material such as steel or wood or the like. The axial dimension of the coating wheels on the surface thereof will determine the width of the pattern of the coating applied to the work. The coating wheels are secured to the shafts 15 and 17 in a readily removable manner so that by removal of the nuts N, the coating wheels can be removed and larger or smaller size wheels in axial dimension secured to the shafts 15 and 17 in order to apply a coating of larger or smaller radial dimension in annular form on a piece of work. It is also possible to utilize different coating wheels of different diameter size in order to take care of thicker and thinner pieces of work to which a coating or coatings are to be applied.

The notched out portion or groove 23 in the trough 18 may not only serve as a guide for the work to be inserted between the coating wheels 19 and 20 but it may also serve as a scraper to effect removal of excess coating.

In operating the apparatus shown in Figs. 1 and 2, the pulley wheel 10 is caused to rotate by a belt, not shown, driven by a pulley on an engine or motor driven shaft, which is also not shown. Rotation of the shaft 11 to which the pulley 10 is fixed effects rotation of the gear 12 which drives the large gear 13 to effect speed reduction. The gear 14 which rotates at the same speed as the gear 13 rotates in the opposite direction to the direction of rotation of gear 16 which is secured to the shaft 17 so that the shaft 17 and the shaft 15 which is secured to the gear 14 rotate at the same relatively slow speeds but in opposite directions as shown in Figure 2. The coating wheels 19 and 20 which are secured to the shafts 15 and 17 respectively, rotate in the bath of coating material such as adhesive in the trough 18 carrying coating material to the corresponding points on their respective outer surfaces which are adjacent each other and at which the work to be coated is located. The rotation of the wheels 19 and 20 effects carrying of the adhesive to the work to form an annular coating on each

side of the work as already described and as shown in the drawing. This coating operation is carried out by the apparatus in a speedy, neat and even manner.

It will be obvious to those skilled in the art that various changes may be made without departing from the spirit of the invention and therefore the invention is not limited to what is shown in the drawing and described in the specification but only as indicated in the appended claim.

What is claimed is:

In apparatus for coating discs with annular coatings on each side of said discs adjacent the periphery thereof, means for driving a pair of work moving and coating wheels in opposite directions so that adjacent portions of said wheels move downwardly and the portions of the wheels remote from each other move upwardly, means for holding a bath of coating material located directly beneath said wheels so that said wheels dip into the bath of coating material, guide means for guiding the piece in work associated with said apparatus and for locating work to be coated accurately between said work moving and coating wheels, said guide means including a stop member located on one side of the space between adjacent portions of the wheels so that work may be inserted between adjacent portions of the coating wheels as far as said stop member, said guide means including a combined guide and scraping member located above the bath of coating material and on the side of the wheels opposite to the side on which the stop member is located, said guide and scraping member being located below said stop member, said guide and scraping member serving to return excess coating material by gravity to said bath, the adjacent portions of said work moving and coating wheels being located sufficiently close to each other so that a disc to be coated which is passed therebetween up to the guide means will engage said wheels and frictional transmission will take place to effect rotation of the disc to be coated whereby the disc will be coated on each side in an area in the form of an annulus, and be guided over the bath by said guide member.

EDWARD H. RAND.
